GASEOUS DISCHARGE TUBE CIRCUIT

Robert M. Critchfield, Anderson, Ind., assignor,
by mesne assignments, to General Motors
Corporation, Detroit, Mich., a corporation of
Delaware

Original application December 31, 1930, Serial
No. 505,787. Divided and this application
August 4, 1933, Serial No. 683,572

2 Claims. (Cl. 176—124)

This invention relates to a circuit for producing a high alternating potential from a low voltage source, and more particularly to a circuit for operating gaseous discharge tubes and similar apparatus requiring relatively high voltage. This application is a division of my co-pending application Serial Number 505,787, which application has become Patent No. 1,952,121.

10 It is one of the objects of the present invention to provide a circuit for the operation of gaseous discharge tubes and similar apparatus that is especially adapted for use on automotive vehicles or in other places equipped with a current source of relatively low voltage. This aim of the present invention is carried out by providing a circuit including induction apparatus in which electrical energy from a relatively low voltage source is interrupted and transformed 15 to a relatively high voltage in order to supply a rapid succession of relatively high voltage impulses suitable for operating a gaseous discharge tube or similar apparatus. The interruption of the current from the low voltage source that is supplied to an induction coil to be transformed to a higher voltage is effected by a periodic circuit breaker that is preferably operated by an electric motor. The motor, as well 20 as the gaseous discharge tube, is preferably supplied with operating current from the low voltage source, which source may be a storage battery or the generator that charges the storage battery.

25 Another object of the present invention is to provide a circuit for the operation of a plurality of gaseous discharge tubes, or similar devices requiring a relatively high operating voltage, from a single low voltage source, and with only a single current interrupting device. This aim 30 of the present invention is carried out by providing a circuit that permits the interruption of the current to a plurality of induction coils by a single current interrupter, each of which induction coils provides the high operating voltage for a gaseous discharge tube or similar device.

Further objects and advantages of the present invention will be apparent from the following description, reference being had to the accompanying drawing wherein a preferred embodiment of one form of the present invention is clearly shown.

In the drawing:

Fig. 1 is a schematic diagram of a circuit embodying the present invention.

Fig. 2 is a schematic diagram showing a modified form of the present invention that is adapted to supply current to two gaseous discharge tubes.

With particular reference to Fig. 1, an induction coil 21, that may be an ignition coil, has a primary winding 22 and a secondary winding 23. One terminal 24 of the winding 22 is connected by a wire 25 to a terminal 26, and through a fuse 28 to a switch contact 30. The switch contact 30 is adapted to be connected through a switch arm 31 to one side of a battery 32, the other side of which battery is grounded at 33. The other terminal 34 of the winding 22 is connected by a wire 35 to a terminal 36 of a condenser 37. The other terminal of the condenser 37 is grounded at 38. The terminal 36 is also connected by a wire 39 to a terminal 40 that is attached and electrically connected to one end of a leaf spring conductor 41 having its other end attached to the circuit breaker lever 42 that is pivoted at 43. The spring 41 electrically connects the terminal 40 with the lever 42, urges the rubbing block 44 against the cam 45 and urges a contact 46 that is carried by the lever 42 into engagement with a stationary contact 47 that is grounded at 49.

The secondary winding 23 has one of its ends connected to the terminal 24 of the primary winding 22, and is thus grounded through the wire 25, fuse 28 and battery 32 to ground at 33. The other end of the secondary winding 23 is connected to a terminal 50, and a conductor 51, that is preferably an insulated cable, to a gaseous discharge tube 52, which gaseous discharge tube is connected to ground at 33. The terminal 50 is connected with a wire 54, the end of which wire is spaced from the terminal 24 to provide a safety spark gap 55.

An electric motor 60, that is preferably small, having brushes 70 and 71 and a field winding 63, is drivingly connected to the cam 45 by a shaft or other suitable driving means 66. The brush 70 is connected to the terminal 26 and to one end of the field winding 63. The other brush 71 is grounded at 75, and is connected to the other end of the field winding 63.

When the switch arm 31 engages the contact 30, the battery 32 is connected to the motor 60 and to the induction coil 21. The rotor rotates, preferably at high speed, to actuate the cam 45 and breaker lever 42, and thereby effects the alternate closing and opening of the contacts 46 and 47, which opening and closing of the contacts interrupts the circuit between the primary

winding 22 and ground at 49. This interruption of the circuit of the primary winding 22 is preferably periodic, and causes a series of current impulses through the primary winding 22, which 5 current impulses produce a high voltage impulse across the secondary winding 23 when the contacts are opened. By thus generating a rapid succession of high voltage impulses which are conducted from the secondary winding 23 to the 10 gaseous discharge tube 52, the gas within the tube is caused to become incandescent.

The wiring diagram in Fig. 2 discloses the manner of using one motor and periodic circuit breaker to control a plurality of induction coils, 15 each of which coils supplies high voltage impulses to a gaseous discharge tube.

In Fig. 2, parts corresponding to the parts in Fig. 1 are referred to by similar reference characters with the affix "a". It will be noted that 20 the primary windings 22a and 22b of the two induction coils 21a and 21b are connected together in series with the circuit interrupter and with a battery having a voltage greater than that of the battery 32 required for operating one gaseous discharge tube. Each of the secondary 25 windings of the induction coils is connected to a gaseous discharge tube. Since it requires no more power to operate a circuit interrupter which controls two coils than it does for operating the circuit interrupter which controls one coil, the same motor can be used for driving the circuit interrupter of Fig. 2 as was used in Fig. 1. Therefore, this motor is not connected with 30 all of the cells of the battery 32a, but with only 35 a sufficient number of them to operate the motor. For example, if a 12 volt battery is required to operate both induction coils 21a and 21b, and a 6 volt motor is used, as indicated in Fig. 2, the motor 60 is not connected with the wire 25a as in the preceding case, but is connected by a separate electric switch 90 to an intermediate tap 91 of the battery 32a, switch 90 being operated concurrently with a switch 31a. While the form of invention shown in Fig. 40 2 is illustrated with two separate gaseous discharge tubes, it will be understood that this form of apparatus can be used for lighting separate sections of a gaseous discharge device. For example, if one induction coil operated by a 6 volt 45 battery will supply the necessary potential and current for operating one gaseous discharge device or section of a certain size and filled with a certain kind of gas, and a larger device or more sections are necessary, the sections will be so 50 divided that each is capable of being operated by a 6 volt induction coil. When a plurality of gaseous discharge devices or a plurality of sections are used, an induction coil is provided for 55 each of the section or number of devices that it is capable of operating, and the primary winding of these coils may be connected in series or in series parallel to a suitable source of operating potential.

While the present specification describes the 60 operation of the circuit with particular reference to gaseous discharge tubes, it is understood that the invention is applicable to other devices requiring an alternating potential of relatively high voltage.

From the foregoing description of the construction and operation of the present igniting circuit for gaseous discharge tubes, it will be apparent that the circuit, in one of its principal aspects, comprises a plurality of high tension 5 gaseous discharge tubes 52a and 52b, a plurality of transformers 21a and 21b each including a primary winding 22a and 22b respectively and a secondary winding 23a and 23b respectively, and each (21a and 21b) having one end of the primary winding 22a and 22b respectively electrically connected to one end of the secondary winding 23a and 23b respectively, a source of direct current 32a, and a circuit interrupter 46a, 47a, the primary windings 22a and 22b, the source of direct 10 current 32a and the circuit interrupter 46a and 47a being connected in series and each of the gaseous discharge tubes 52a, 52b, being ignited by the potential across only one of the secondary windings 23a and 23b respectively. 20

Some of the advantages of the circuit herein disclosed and described are as follows:

(1) A plurality of gaseous discharge tubes may be ignited from a common current source, and have potentials individually applied thereto so 25 that the operation of one tube is not dependent upon that of the other.

(2) The series connection of the primary windings, current source and circuit interrupter in the igniting circuit permits the use of a common current source and interrupter for the plurality of transformers and gaseous discharge tubes, and also effects low current consumption with the high ratio transformers.

(3) The electrical connection of the primary 35 windings of each transformer to the secondary windings thereof makes possible the use of a common ground or connection in the circuit for igniting the plurality of gaseous discharge tubes.

While the form of embodiment of the present 40 invention as herein disclosed, constitutes a preferred form, it is to be understood that other forms might be adopted, all coming within the scope of the claims which follow.

What is claimed is as follows:

1. As an igniting circuit for gaseous discharge tubes, the combination comprising, a plurality of high tension gaseous discharge tubes, a plurality of transformers each including a primary winding and a secondary winding and each having 50 one end of the primary winding electrically connected to one end of the secondary winding, a source of direct current, and a circuit interrupter, the primary windings, the source of direct current and the circuit interrupter being connected in series and each of the gaseous discharge tubes being ignited by the potential across only one of the secondary windings. 55

2. In a gaseous discharge tube igniting circuit, the combination of a plurality of high tension 60 electrical discharge tubes, a plurality of transformers, each including a primary winding and a secondary winding, a source of potential, and a circuit interrupter, all of the primary coils, the source of potential, and the circuit interrupter 65 being connected in a series circuit, and each of the high tension discharge tubes being energized by one only of the secondary coils.

ROBERT M. CRITCHFIELD.
